UNITED STATES PATENT OFFICE.

HEINRICH FRANZ EDMUND BAESLER, OF DRESDEN, GERMANY, ASSIGNOR TO AKT. GES. VORM SEIDEL & NAUMANN, OF DRESDEN, GERMANY, A CORPORATION OF GERMANY.

ARRANGEMENT OF THE PAPER-PRESSING ROLLERS OF TYPEWRITING MACHINES.

1,426,243.

Specification of Letters Patent. Patented Aug. 15, 1922.

Application filed October 12, 1920. Serial No. 416,581.

(GRANTED UNDER THE PROVISIONS OF THE ACT OF MARCH 3, 1921, 41 STAT. L., 1313.)

To all whom it may concern:

Be it known that HEINRICH FRANZ EDMUND BAESLER, director of a company, a citizen of the German Republic, residing at 5 Dresden, Schumannstr. 24, Germany, have invented certain new and useful Improvements in an Arrangement of the Paper-Pressing Rollers of Typewriting Machines (for which I have filed applications in Germany May 25, 1917, utility Patents 664,072, 10 664,073, and 664,074; in Austria May 24, 1919, Patent No. 85,613, and in Switzerland June 30, 1919, Patent No. 84,547), of which the following is a specification.

15 This invention relates to type writing machines, especially to the rollers serving to press the paper sheet or the layers of sheets against the impression cylinder.

For the purpose of lifting these rollers 20 from the impression cylinder, when a sheet or the layer of sheets to be written on is inserted and adjusted, sleeves or collars carrying lugs or stops are provided, which sleeves are adjustably mounted on the axle upon 25 which the bearing levers for the pressing rollers are also loosely mounted, said sleeves being arranged in such a manner, that when the axle which carries the bearing levers is rocked, the lugs carried by the bearing levers 30 are caused to swing against the action of springs which serve to hold the rollers in engagement with the impression cylinder.

In order to obtain a uniform pressure of 35 the rollers against the impression cylinder, said pressure corresponding to the thickness of the layers of paper and to the diameter of cylinders, which have been already ground off, the rollers are pressed against the impression cylinder by means of springs, the 40 tension of which can be adjusted. These springs, which have one of their ends engaging with the bearing levers of the rollers of one side of the impression cylinder, have their opposite ends secured by means of adjustable stops or lugs with levers which act 45 in their turn upon the bearing levers for the rollers of the other side of the cylinder.

In order to retain the rollers in released 50 position, a locking member is moved by the paper releasing lever into such a position, that it engages with the lever which lifts the rollers, said lever also being rocked by the releasing lever into release position, and locks said lifting lever in this position. The

releasing lever actuates the locking member 55 by means of a pin projecting into a slot of said member, the slot suitably being made of such a width, that the pin has some play at the return movement in order to enable the lifting lever, which has been oscillated 60 slightly beyond the locking position to engage one end of the locking member.

The subject matter of the invention is illustrated in the accompanying drawings, in which

Fig. 1 is a perspective view of the left hand portion.

Fig. 2 a perspective view of the right hand portion of the carriage of a type writing machine embodying my invention.

Fig. 3 is a perspective rear view,

Fig. 4 a vertical cross section,

Fig. 5 a perspective detail view, in which the roller for pressing the paper against the impression cylinder is shown in lifted or released position.

Figs. 6 and 7 are detail views showing the different positions assumed by the locking member.

The impression cylinder 5 is mounted in a 80 known manner in the cylinder frame which comprises the side parts 1 and the transverse rods 2, 3 and 4 (Figs. 1 and 2). On the transverse rod 4 bearings 6 are provided, in which an axle 7 is mounted to rock. The 85 bearing levers 8 carrying the axle 9 for the rollers 10 are also mounted to rock or turn on said axle 7. In addition to the levers 8, sleeves or collars 11, 12 or the like are mounted upon the axle 7 in such a manner, that 90 they can be exactly adjusted and secured to said axle by means of the set screws 13. On each of the sleeves 11 a lug or stop 14 (Figs. 1 and 4) is provided, which acts upon a pin 15 secured to the lever 8. In accordance 95 with the adjustment of the sleeve 11 upon the axle 7 the levers 8 are rocked more or less when the axle 7 is rocked and the pressing rollers 10 are thus lifted for a corresponding distance from the impression cylinder 100 5. On each of the sleeves or collars 12 a lug or stop 16 is provided, which projects through a slot in the rod 4 into the path of a lug 21 of the bearing lever 18 of the rear roller 19, said bearing lever being arranged 105 on the axle 17; the lug 16 also causes a rocking movement of the lever 18 against the action of the spring 20, so that, when the

axle 7 is rocked, the roller 19 is lifted from the impression cylinder 5 simultaneously with the pressing rollers 10. The course of the bearing levers 8, 18 can be exactly regulated by the adjustment of the sleeves 11, 12 on the axle 7. The rotating movement of the axle 7 for the purpose of lifting the pressing rollers can be effected in the manner to be described further on.

- 10 The impression cylinder 5 is mounted upon the axle 22 and is secured in its bearings by a device not shown. At the rear side of the transverse rod 4 the axle 17 is mounted in the bearings 23 and on said axle 15 the bearing levers 18, which carry the axle 24 for the rear pressing roller 19, are arranged in such a manner, that they can loosely rotate on this axle, (Figs. 3 and 4). Furthermore levers 25 are mounted to lock 20 on the axle 17 and to each of these levers one end of spring 26 is connected, the other end of each of which springs being secured to one of the levers 8. The levers 25 each carry a screw-bolt 27, which can be fixed by 25 a cheek-nut 26 and which abuts against an angle 28 provided on the lever 18. The spring 20 tends to move the levers 8 and rollers 10 and, through the medium of the screw-bolt 27 and angle 28, the levers 18 and roller 19 uniformly against the impression cylinder 5. By the adjustment of the screw-bolt 27 the tension of the spring can be adjusted in accordance with the diameter of the impression cylinder.
- 30 The releasing lever 29 is pivotally mounted on the pin 30 of the side part 1 of the cylinder frame and carries a pin 31 which engages in an eccentric slot 32 of the locking member 33, which is pivoted on the pin 40 34 of the side plate of said frame. One edge of the lever 29 engages with a bent extension 35 of a lever 36 formed in one piece with the axle 7 or secured upon the same; accordingly the lever 29 actuates said lever 45 36 and thereby also the axle 7 in the direction of the arrow (Fig. 2).

If the releasing lever 29 is turned in the direction of the arrow (Fig. 2), it actuates the lever 36 rocks the axle 7, oscillates the 50 lever 8 and lifts the rollers 10 from the impression cylinder 5. Simultaneously with the rocking of the axle 7 the releasing lever 29 through the medium of the pin 31 and slot 32 moves the locking member 33 into 55 the position shown in Fig. 6. At the release of the lever 29, which is moved slightly beyond the locking position in order to allow the locking member 33 to pass the bent extension, the lever 36 is moved slightly 60 rearwardly by the influence of the springs 20 acting upon the rollers, until the extension 35 of said lever engages with the locking member 33, so that a mutual locking of the parts is effected. The slot 32 is sufficiently wide that during the short rearward

movement the pin 31 can not act upon the locking member.

The release of the locking member 33 is effected by the return movement of the releasing lever 29 when the locking member 33 70 is restored to the position shown in Fig. 2.

As the movement of the locking member in each direction is governed by its mechanical connection with the lever 29 it is not necessary to provide a spring for said locking member. The arrangement of the remaining parts necessary for guiding the paper can be effected as desired.

Having thus particularly described the nature of my invention, what I claim as new 80 and desire to secure by Letters Patent of the United States is:

1. In a typewriting machine, a cylinder frame, an impression cylinder mounted to rotate in said frame, a rock shaft carried by 85 the frame, a pair of bearing levers mounted to rock on said rock shaft, a roller journaled in said bearing levers and adapted to engage said impression cylinder, a second pair of bearing levers carried by said frame, a 90 second roller journaled in the latter bearing levers and adapted to engage said impression cylinder at a point on its periphery at a distance from said first-named roller, spring means tending to maintain said rollers in engagement with said impression cylinder and means carried by said rock shaft and engageable with one of each of said pairs of bearing levers to rock said levers and move said rollers out of engagement with said impression cylinder when said rock shaft is actuated.

2. In a typewriting machine, a cylinder frame, an impression cylinder mounted to rotate in said frame, a rock shaft mounted 105 on said frame, a pair of bearing levers mounted to rock on said rock shaft, a roller journaled in said bearing levers and movable into engagement with said impression cylinder, a second pair of bearing levers 110 pivoted to said frame, a second roller journaled in said second pair of bearing levers and adapted to engage said impression cylinder at a point removed from said first-named roller, an arm pivotally mounted on 115 said frame adjacent one of said second-named pair of bearing levers, adjustable means carried by said arm and engaging the bearing lever just mentioned, a spring extending between said arm and one of the 120 bearing levers carried by said rock shaft, and means carried by said rock shaft and engageable with one of the bearing levers of each of said rolls to rock said levers and move said rollers out of engagement with 125 the impression cylinder when the rock shaft is actuated.

3. In a typewriting machine embodying an impression cylinder and rollers for pressing paper against the impression cylinder, means 130

for releasing said rollers from engagement with the impression cylinder comprising a pair of rock shafts, a pair of bearing levers for one of said rollers mounted to rock on 5 each of said rock shafts, a spring tending to rock said rock shafts to bring the rollers against the impression cylinder, a sleeve secured to one of said rock shafts, and lugs carried by said sleeve engaging 10 one of each of said pairs of levers when said rock shaft is actuated.

4. In a typewriting machine embodying an impression cylinder and rollers for pressing paper against said cylinder and a frame 15 in which said cylinder and rollers are mounted, means for moving said rollers out of engagement with said cylinder comprising a rock shaft mounted in said frame, a pair of bearing levers carrying one of said rollers and mounted to rock on said rock shaft, means carrying the other of said rollers rockably mounted on said frame, spring means connecting one of each of said pairs of levers and tending to press said rolls 20 against said cylinder, a sleeve secured to said rock shaft, and lugs carried by said sleeve and engaging one of each of said pairs of levers for moving said rolls out of engagement with said cylinder when said 25 rock shaft is actuated.

5. In a typewriting machine embodying an impression cylinder and a pair of rollers for pressing paper against said cylinder and a frame carrying said cylinder and rollers, means for moving said rollers out of 30 engagement with said impression cylinder comprising a rock shaft mounted in said frame, a pair of bearing levers for one of said rollers mounted to rock on said rock shaft, a second pair of levers for the other of said rollers rockably mounted on said frame, a rockable member mounted coaxially with said last-named bearing levers and provided with adjustable means 35 engaging one of said levers, and a spring connecting said member and one of said first-mentioned levers.

6. In a typewriting machine embodying

an impression cylinder, a pair of rolls for pressing paper against said cylinder and a frame in which said cylinder and rolls are mounted, means for moving said rolls out of engagement with said cylinder comprising a rock shaft mounted in said frame, bearing levers for one of said rolls mounted to rock on said rock shaft, a second pair of bearing levers for the other of said rolls rockably mounted on said frame, means secured to said rock shaft to engage and rock one of each of said pairs of bearing levers, 50 an arm secured to said rock shaft for actuating the same, and means for securing said arm against movement when said rock shaft is rocked into roller-releasing position.

7. In a typewriting machine embodying an impression cylinder, a pair of rolls cooperative therewith and a frame in which said cylinder and rollers are mounted, means for moving said rollers out of engagement 55 with said cylinder comprising a rock shaft mounted in said frame, a pair of bearing levers for one of said rolls mounted to rock on said rock shaft, a second pair of bearing levers for the other of said rolls rockably mounted on said frame, means secured to said rock shaft and adapted to engage and rock said levers to move said rolls away from said cylinder when said rock shaft is actuated, an arm secured to said rock shaft 60 for actuating the latter, and means for securing said arm in the roller release position, said means including a member pivotally secured to the frame and adapted to engage one end of said arm and provided with a slot, a finger lever mounted on said frame, and a pin carried by said finger and engaging said slot for actuating said slotted member.

In testimony whereof I have hereunto set 70 my hand in presence of two subscribing witnesses.
